UNITED STATES PATENT OFFICE.

CHARLES A. FRENCH AND LAURANCE E. GOIT, OF CHICAGO, ILLINOIS, ASSIGNORS
TO INTERNATIONAL HARVESTER COMPANY, OF CHICAGO, ILLINOIS, A CORPORA-
TION OF NEW JERSEY.

INSTANTANEOUS FUEL BURNER AND METHOD OF BURNING FUEL.

Application filed June 8, 1922. Serial No. 566,886.

To all whom it may concern:

Be it known that we, CHARLES A. FRENCH and LAURANCE E. GOIT, citizens of the United States, and residents of Chicago, in the county of Cook and State of Illinois, have invented certain new and useful Improvements in Instantaneous Fuel Burners and Methods of Burning Fuel, of which the following is a full, clear, and exact specification.

Our invention relates to fuel burners and particularly to burners using kerosene, distillate and the heavier oils for fuel and to a method of burning fuel.

The ordinary burner using fuel oil (kerosene or heavier) must be heated from an external source to a temperature sufficiently high to vaporize the fuel before it can be started. This preheating requires from two to ten minutes before the burner is ready for normal operation. In automotive steam power plants this delay in starting the burner is entirely too great and has been one very material factor in limiting the adoption of steam propelled motor vehicles.

The principal object of our invention therefore is to provide a burner utilizing relatively heavy oil for fuel that may be started instantly (as by a spark plug) and will burn from the start with a clean, blue flame, there being no carbon deposits or soot formed at any stage of the operation of the burner no matter how long or short time it may continue in operation.

Briefly stated, our invention involves a burner and method of burning fuel in which the fuel is finely divided by blowing it over a sharp atomizing edge with an air blast which supplies only enough air to form a combustible mixture with the very small amount of the fuel that is vaporizable at low temperatures. This mixture is then ignited and as it burns in the presence of the heavier particles of fuel, more fuel is vaporized by the heat therefrom and proportionately more air added to form a combustible mixture therewith. This stage of operation continues progressively, that is, more heat is generated, more fuel vaporized and more air added so as to keep a blue flame burning until that point is reached at

which the combustion may be accelerated by addition of sufficient air to completely burn all the fuel with a blue flame.

Reference will now be had to the drawings, in each of the figures of which we have shown a burner embodying the principles of our invention and adapted to carry out our improved process of combustion.

In Figures 1 and 2 we supply the fuel directly to the atomizing edge by an impeller, while in Figure 3 the fuel is distributed to the atomizing edge by an air blast.

In Figure 1, our improved burner has a casing 5 closed at its upper end by a hood 6 having an air inlet 7 controlled by a throttle valve 8. A vertical shaft 9 journaled in the hood 6 is driven by a belt pulley 10 secured to its upper end and carries an air propelling fan 11 which draws in air through the inlet 7 and a central outlet 12 in the hood delivering it radially from the fan blades into the burner casing. The shaft extends downward into the casing below the fan and at its lower end supports a bowl 13 having a plurality (preferably 4) of hollow radial arms 14 through which fuel supplied to the bowl from a pipe 15 is distributed. An annular grating 16 has a plurality of rows of graduated perforations 17 of increasing diameter from top to bottom and extends upwardly into the casing being secured thereto by a flange 18. An annulus 19 is secured to the top of the grating and has a sharp circular edge 20 for atomizing the fuel. An inner grating 21 is secured within the outer grating 16 by means of bolts 22 and has similar graduated perforations 23. At its top side the grating 21 has an annular lip 24 extending into close proximity to the edge 20 whereby a narrow annular opening 25 is provided for the passage of the fuel and a restricted amount of air. An annular deflector 26 directs the passage of air from the fan 11 toward the center so that air is supplied to the central grating 21 as well as to the outer grating 16. A spark plug 27 or other form of igniter extends through the casing into the combustion zone 28 between the two gratings a short distance below the atomizing edge where the fuel is ignited.

In operation, the pulley 10 drives the fan 11 to draw in air through the inlet 7 to which air may be supplied at atmospheric pressure or under slight pressure from a 5 blower. The air is delivered by the fan under slight pressure to the casing 5 where it divides, part passing to the outside of the grating 16 and part to the inside of the grating 21 from where it passes through the 10 perforations 17 and 23 into the combustion zone. Fuel is supplied to the bowl 13 from the fuel pipe 15 and is distributed by centrifugal force through the arms 14 and small 15 perforations 29 in a finely divided liquid state to the surface of the ring 19 near the sharp edge 20 from which it is blown in a finely atomized condition by the blast of air flowing through the narrow opening 25. The velocity and pressure of the air flowing 20 over the atomizing edge are considerably increased by the arms 14 which operate as impeller blades on the air.

As the fuel and air leave the sharp edge 20, a small amount of the fuel will be 25 vaporized and mix with the air to form a combustible mixture which is ignited by the spark plug 27. This mixture burns as it passes downward in the combustion space between the grates, the great excess of fuel 30 retarding the combustion so that not enough heat is generated to decompose the unburned particles but sufficient is developed to partly vaporize the particles and allow the vapor to diffuse evenly and, as the fuel 35 particles and vapor pass the openings 17, 23, only enough air is supplied to continue the combustion at a low rate or below the rate of complete decomposition of the fuel. This combustion is relatively cold and, as 40 it progresses, the fuel vapors are progressively cracked into smaller and smaller particles, the tendency of which to decompose is less noticeable the smaller they become. Eventually a point is reached at which the 45 hydro-carbon particles are cracked down so that the combustion may be accelerated to the greatest possible extent without producing decomposition of the fuel. The result is that our burner burns with a clean, short, 50 blue flame as soon as it is started and there is absolutely no deposit of carbon or formation of soot.

The burner of Figure 2 operates similarly to that of Figure 1 but differs slightly in details of construction. Air is supplied under pressure to the inlet 30 and drives the turbine 31 mounted on the shaft 32 which carries a bowl 33 at its lower end to receive fuel from a supply pipe 34. The bowl has 55 a plurality of hollow radial arms or pipes 35 which distribute the fuel to the atomizing edge 36 in the same manner as in Figure 1. The mixture is fired by an igniter 37 and additional air is supplied through the

graduated perforations 38 and 39 in the inner 65 and outer gratings 40 and 41 respectively.

In Figure 3 the burner casing comprises upper and lower sections 43 and 44 secured together by bolts 45. The upper section carries a shaft 46 and has an inlet 47 through which air is supplied to the impeller or fan 48, the fan also serving to distribute fuel supplied through a pipe 49. The fan is driven by a pulley 50 mounted on the shaft 46. The air and fuel are 70 thrown outward by the impeller against the curved inner wall of the casing, the fuel and some of the air following the wall down to the atomizing edge 51 from which the fuel is blown in finely atomized condition into 75 the combustion space 52 where it is fired by an igniter 53 and burns slowly. Additional air is supplied through perforations 54 in the grating 55 to progressively increase the combustion until the fuel is 80 vaporized and cracked to such an extent that when it issues from the annular opening 56 into the path of the air coming down through the grating nozzle 57 at high 85 velocity it will burn with a clean, blue 90 flame. The velocity of the air through the nozzle 57 is quite high and the combustion in the chamber 52 is not necessarily carried as far as it is in the combustion chambers of Figures 1 and 2 before sufficient 95 air is added for complete combustion. We have found if the air is supplied to the partly burned and cracked fuel at high velocity, that this velocity may be substituted for a portion of the precombustion, 100 that is, the precombustion may be stopped at an earlier stage and the final stage completed without the formation of soot or carbon deposits.

In a burner constructed according to our invention with the atomizing edge having a circumference of approximately 24 inches, the bowl having four fuel distributing arms or vanes, the fan running at approximately 3,000 R. P. M. and the burner consuming about 35 pounds of fuel per hour, each incremental length of the edge will receive fuel 200 times per second, the entire circumference receiving .0096 pounds of fuel per second which results in a very fine atomization. The fuel is delivered about $\frac{1}{8}$ inch above the edge and its fine distribution prevents liquid particles of any appreciable size from being carried past the atomizing edge by the air current.

Having thus described our invention, what we claim as new and desire to secure by Letters Patent is:

1. That method of burning liquid fuel which comprises atomizing the fuel by blowing it over a sharp edge with a supply of air insufficient for complete combustion, 125 burning a portion of the fuel in the insuf-

5 ficient air supply to vaporize the fuel and crack it into simpler hydrocarbons, adding more air and burning more fuel to increase the vaporization and cracking, and continuing the combustion with the addition of progressively increasing quantities of air and progressively increasing cracking of the fuel until that point is reached at which air sufficient for complete combustion may be 10 added and the combustion completed without decomposition of the fuel.

2. That method of burning fuel which comprises mixing the fuel in a relatively cool state with an amount of relatively cool 15 air insufficient for complete combustion, burning a portion of the fuel in the insufficient air supply at a temperature below that of decomposition of the fuel, progressively adding quantities of air sufficient to continue 20 the combustion at a temperature sufficient to vaporize and crack the fuel but insufficient to decompose the fuel and finally adding sufficient air for complete combustion of the fuel.

25 3. In a burner, the combination of a circular grating having an annular atomizing edge, means providing a restricted passage adjacent the edge, means for supplying fuel to the edge, means for supplying a blast of air through the restricted passage and over the edge whereby 30 the fuel is atomized and mixed with the air, and means for igniting the mixture.

35 4. In a burner, the combination of a grating having an atomizing edge, means providing a restricted passage adjacent the edge, means for supplying fuel to the edge, means for supplying a blast of air through the restricted passage and over the edge whereby 40 the fuel is atomized and mixed with the air, means for igniting the mixture, and means for supplying additional air to the mixture after it has been ignited.

45 5. In a burner, the combination of a grating having an atomizing edge, means providing a restricted passage adjacent the edge, means for supplying fuel to the edge, means for supplying a blast of air through the restricted passage and over the edge whereby 50 the fuel is atomized and mixed with the air, means for igniting the mixture, and means for successively adding further quantities of air to the burning mixture.

55 6. In a burner, the combination of a grating having an atomized edge, means providing a restricted passage adjacent the edge, means for supplying fuel to the edge, means for supplying a blast of air through the restricted passage and over the edge whereby 60 the fuel is atomized and mixed with the air, means for igniting the mixture, and means for successively adding progressively increasing amounts of air to the burning mixture.

65 7. In a burner, the combination of an an-

nular grating having perforated sides and a sharp annular edge at one end, an annular lip providing with the sharp edge a constricted annular passage, means for supplying fuel to the edge, means for forcing air through the annular passage to atomize the fuel, means for igniting the atomized fuel and air after it has left the edge, and means for supplying additional air to the burning mixture through the perforations in the grating.

8. In a burner, the combination of two concentric perforated gratings providing a combustion zone therebetween, an annular sharp edge and lip on the respective gratings providing a restricted annular passage communicating with the combustion zone, means for creating a blast of air and fuel over the sharp edge and into the combustion zone, and means for supplying additional air thereto through the perforations in the gratings.

9. In a burner, the combination of a casing, means providing an annular combustion chamber therein, centrifugal means above the chamber for supplying a mixture of air and fuel thereto, means extending through the casing and into the chamber for igniting the mixture in the combustion chamber, and means for supplying additional air to the burning mixture through the walls of the combustion chamber.

10. In a burner, the combination of a casing, means providing an annular combustion chamber therein, centrifugal means at one end of the chamber for supplying a mixture of air and fuel to one end of the combustion chamber, means extending through the casing for igniting the mixture in the combustion chamber near said end, and means for supplying a successively increasing amount of air to the burning mixture through the walls of the combustion chamber with the largest amount of air coming in at the other end of the chamber.

11. In a burner, the combination of a casing, a shaft rotatably mounted therein, a grating in the casing having an annular sharp edge concentric with the shaft, means rotatable with the shaft for distributing fuel to the sharp edge, means for directing a blast of air over the sharp edge to atomize the fuel, means for igniting the mixture of air and fuel as it leaves the sharp edge, and means for supplying additional air to the burning mixture.

12. In a burner, the combination of a casing, a shaft rotatably mounted therein, a grating in the casing having an annular sharp edge concentric with said shaft, a bowl rotatable with the shaft and having a plurality of hollow arms terminating adjacent the sharp edge and adapted to deliver fuel thereto, means for supplying fuel to the bowl, and an air impeller rotatable with the

shaft for directing a blast of air over the sharp edge and through perforations in the grating.

13. In a burner, the combination of a casing, a shaft rotatably mounted therein, two concentric perforated gratings providing an annular combustion chamber, an annular sharp edge and lip on the respective gratings coaxial with the shaft, a bowl rotatable with the shaft and having a plurality of hollow arms terminating adjacent the sharp edge, means for supplying fuel to the bowl, means rotatable with the shaft for directing a blast of air between the sharp edge and lip, means for igniting the fuel and air leaving the lip, and means for supplying additional air to the burning mixture through the perforations in the gratings.

14. In a burner, the combination of a casing, a pair of concentric gratings mounted in the casing and spaced apart to form a combustion chamber between them, means for supplying and directing a combustible mixture to said chamber, means for igniting the mixture in the chamber, and means for supplying additional air to the chamber through perforations in the gratings.

15. In a burner, the combination of a casing, a pair of concentric perforated gratings mounted in the casing and spaced apart to form a combustion chamber between them, means for supplying a combustible mixture to the chamber, and means for igniting the mixture in the chamber, the perforations in the gratings being so arranged and formed

that additional air may be progressively added to the burning mixture in successively increasing quantities.

16. In a burner, the combination of a casing, a pair of concentric gratings mounted in the casing and arranged to form a combustion chamber between them gradually increasing in size from one end to the other, means for supplying a combustible mixture to the chamber at its smaller end, means for igniting the mixture, and means for adding additional air through the walls of the gratings to the chamber at its larger end.

17. In a burner, the combination of a casing, a pair of gratings forming a combustion chamber between them and carried by said casing, centrifugal means for supplying fuel to said chamber including a plurality of hollow arms terminating adjacent the chamber, means for supplying air to the chamber, and means for igniting the mixture in the chamber.

18. In a burner, the combination of a casing, a pair of spaced concentric gratings mounted in the casing, a vertical shaft rotatably mounted in the casing, a bowl rotatable with the shaft and adapted to deliver fuel between the gratings, and an impeller rotatable with the shaft and positioned above the bowl for directing a blast of air downwardly between the gratings.

In testimony whereof we affix our signatures.

CHARLES A. FRENCH.
LAURANCE E. GOIT.
